AUTOMOBILE IDENTIFICATION MARKER

Irvin W. Sponsler, 12126 Kimberley Lane,
Houston, Tex. 77024

Filed Dec. 6, 1965, Ser. No. 84

Term of patent 14 years

(Cl. D1—12)

FIG. 1 is a perspective view taken from the front, top, and left end of an automobile identification marker showing my new design; and

FIG. 2 is a perspective view taken from the rear, bottom and right end thereof.

The dominant features of my design reside in the portions shown in full lines.

I claim:

The ornamental design for an automobile identification marker, as shown and described.
